(57) **CLAIM**

The ornamental design for a ceiling fan as shown and described.

DESCRIPTION

FIG. 1 is a top perspective view of a ceiling fan, showing our new design.

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a right-side view thereof; and,

FIG. 8 is a left-side view thereof.

Broken lines illustrate portions of the ceiling fan that form no part of the claimed design. Broken jagged break lines shown on the ceiling fan depict a symbolic break in length and form no part of the claimed design.

1 Claim, 8 Drawing Sheets
